MEANS FOR AND METHOD OF MOUNTING STEMMED ARTICLES

Filed Feb. 8, 1940

UNITED STATES PATENT OFFICE

2,245,021

MEANS FOR AND METHOD OF MOUNTING
STEMMED ARTICLESAnthony W. Tripp and Jacob D. Stiriss, New York,
N. Y., assignors to Slidette Corp., New York,
N. Y.

Application February 8, 1940, Serial No. 317,839

4 Claims. (Cl. 24—207)

This invention relates to means for and methods of mounting stemmed articles.

Certain ornaments or buttons provided with stems cannot be attached to a support by riveting, often because the article or button is too fragile to withstand the shock of a riveting machine. It is therefore an object of this invention to provide an extremely simple and economical method of mounting said articles on a support therefor without the danger of injuring the articles.

A further object of this invention is to provide a strong, rugged and durable mounted stemmed article, which shall be relatively inexpensive to manufacture and practical and efficient to a high degree.

Other objects of this invention will in part be obvious and in part hereinafter pointed out.

The invention accordingly consists in the combination of steps, features of construction, combinations of elements, and arrangement of parts which will be exemplified in the method and construction hereinafter described, and of which the scope of application will be indicated in the following claims.

In the accompanying drawing, in which is shown one of the various possible illustrative embodiments of this invention,

Fig. 1 is a front elevational view of a portion of a garment provided with tape connected slider fasteners on which are mounted stemmed buttons or ornaments, in accordance with the method embodying the invention;

Fig. 2 is a rear elevational view of the structure shown in Fig. 1;

Fig. 3 is an enlarged, cross-sectional view taken on line 3—3 of Fig. 1;

Fig. 4 is a cross-sectional view taken on line 4—4 of Fig. 3;

Fig. 5 is a cross-sectional view taken on line 5—5 of Fig. 3;

Fig. 6 is a perspective inside view of the button or ornament before it is mounted on the slider fastener;

Fig. 7 is a perspective view of the part of the slider fastener to which the button shown in Fig. 6 is attached;

Figs. 8 and 9 are elevational, cross-sectional views illustrating two steps in the method of attaching the button shown in Fig. 6 to the part shown in Fig. 7;

Fig. 10 is a cross-sectional view taken on line 10—10 of Fig. 9; and

Fig. 11 is a perspective view of an instrument

which may be used to attach the button to the part on which the button is mounted.

Referring now in detail to the drawing, 10 designates a garment formed with a split or opening 11 adapted to be closed by tape connected slider fastener construction 12, including slider fasteners 13 on which are mounted buttons or ornaments 15, in accordance with the method embodying the invention.

The construction disclosed in the drawing is but one illustration of a stemmed article attached to a support therefor, in accordance with the invention, it being understood that stemmed articles may be mounted on a large variety of supports in accordance with the invention disclosed herewith.

Stitched to the garment 10 at the split or opening 11, are elongated flexible strips 18 having adjacent marginal beaded edges 19. The tape connected fastener 12 construction comprises an elongated piece of flexible tape 20, to which the fasteners 13 slidably receiving the beaded edges 19, are attached.

The fasteners 13 may be of any suitable construction. As shown in the drawing, for the purpose of illustration, each fastener 13 comprises a pair of metal parts 23 and 24. Part 23 has a flat wall 25 from the sides of which extend parallel flanges 27. Wall 25 is formed with a central outwardly pressed, recessed portion 30 formed with a transverse slot 31. Extending from the ends of wall 25, are tabs 33, for the purpose hereinafter appearing.

Part 24 has a flat wall 23, parallel to wall 25, and likewise formed with parallel flanges 36. The flanges 36 are aligned with and spaced from the flanges 27, forming slots 38 therebetween to receive the strips 18. The beaded edges 19 of strips 18 are disposed on the inner sides of the flanges 27, 36, as shown in Fig. 4 of the drawing.

Wall 35 is formed, at the outer ends thereof, with open ended depressed portions 37, and the tabs 33 are formed with tongues 39 bent into said depressed portions, to attach the parts 23 and 24 together. Tabs 33 are formed with shoulders 40 contacting the undersides of the depressed portions 37, the latter being formed with notches 37a, through which the tongues 39 pass. Thus, the shoulders serve to properly space the walls 25 and 35 from one another.

Wall 35 may be formed with a central depressed portion 43, having an opening 44; and the tape 20 may be attached to part 24 by means of a rivet 45 passing through said opening, the head

of the rivet engaging the tape and pressing the same into said depressed portion.

The button or ornament 15 may be attached to part 23 before the parts 23 and 24 are attached together. Although many ornaments may be attached to the part 23 by riveting, some ornaments cannot be attached thereto in such manner because the ornaments are too fragile to withstand the shock of a riveting machine. In accordance with the present invention, the button 15 is attached to part 23 without necessity for riveting, and in such a manner as to preclude injury to the button or ornament, as will appear hereinafter.

The button or ornament 15 is provided with a stem 60. The stem is usually of round wire stock, and the outer end thereof may be flattened to form a transverse tongue 61 at the outer end of the stem.

As shown in Fig. 8 of the drawing, the button 15 has a rounded head 62 which may contact the wall 25. In such event, the shoulder 64 between the stemmed portions 60 and 61 contacts the outwardly pressed portion 30 of part 23. The tongue 61 passes through the slot 31 in the outwardly pressed portion 30 and extends beyond the inner surface of wall 25.

In such position, the tongue 61 may be engaged by a tool 65 and twisted to attach the button to part 23. The tool 65 comprises a shank 66 having a handle 67 at one end and formed with a diametric slot 68 at its outer end, increasing in width from its outer end to form spaced, parallel shearing edges 68a. The distance between said edges is just sufficient to admit the flat tongue 61. The tool is applied as shown in Fig. 8 with the axis of the tool in alignment with the axis of the stem 60, with the inner end of the tongue 61 projecting into the slot 68, and with the end of the tool contacting the inner surface of wall 25 and covering the recess formed by outwardly pressed portion 30.

The cross-section of the tongue 61 is substantially the same as the shape of slot 68 so that the tongue fits into the slot; and by turning the tool 65 about its longitudinal axis (and hence about the axis of the stem 60) the tongue is twisted to the position shown in Figs. 9 and 10, for fixing the button or ornament to said part 23. As the tool 65 is twisted, the edges 68a of the tool will shear off whatever portion of the tongue 61 projects beyond the inner surface of wall 25, so that the twisted part of the tongue is wholly within the recess in depressed portion 30. It will be noted that the stem will be twisted without submitting the ornament to any stress, as the stress will be taken up by the slotted wall 25, without transmitting the stress to the ornament.

It will thus be seen that there is provided an

article and method in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. In combination, a member having a recess, the bottom wall of said recess being formed with a slot, and an ornament having a head and a stem, said stem having a round part extending from the head, and a flattened part extending from the round part, and passing through said opening, and said flattened part being twisted to attach said ornament to said member, the shoulders formed at the end of the round part adjacent the flat part contacting the undersurface of the slotted wall, and said twisted part being disposed wholly within said recess.

2. In a method of attaching an ornament comprising a head and a stem having a flat portion, to a member having a slot, consisting in passing said flat portion through said slot and then twisting said portion about the axis of said stem to attach said ornament to said member, with a tool having shearing edges to shear off a portion of the same during the twisting operation.

3. In combination, a member having a wall and an outwardly pressed portion constituting a recess having a bottom wall spaced from the first wall and formed with a slot, a second member having a head and a round stem formed with a flat portion at its outer end passing through said opening, into the recess formed by said outwardly pressed portion, and twisted about the axis of said stem, to attach said button to said member, said twisted portion being disposed wholly within said recess, and said head having a portion contacting the first wall.

4. A method of the character described, consisting in passing a flat stem on an ornament through a slot in an outwardly pressed portion of a support for said ornament, with the flat portion extending beyond the recess formed by said outwardly pressed portion, then gripping the portion of said stem which projects beyond said recess with a tool having shearing edges on opposite sides of the faces of said item, and twisting said tool to twist said tongue, and shear off the portion thereof which projects beyond said recess.
